UNITED STATES PATENT OFFICE

97,233

DESIGN FOR AN ELECTRIC CABLE TERMINAL

Louis A. Koch, Jr., Louisville, Ky.

Application January 16, 1934, Serial No. 50,420

Term of patent 14 years

To all whom it may concern:

Be it known that I, Louis A. Koch, Jr., a citizen of the United States, residing at Louisville, in the county of Jefferson and State of Kentucky, have invented a new, original, and ornamental Design for an Electric Cable Terminal, of which the following is a specification, reference being had to the accompanying drawing, forming part thereof.

Figure 1 is a perspective view of an electric cable terminal, showing my new design and

Figure 2 is a perspective view of the terminal in completed form.

The dominant features of this design are the provisions of upstanding ledges on the sides of the base plate of sufficient height and extent to mask the otherwise open sides of the parallel plates, and the equally important frustro-conical ledge parallel with the free edge of the upper plate and intermediate the latter edge and the center opening.

I claim:

The ornamental design for an electric cable terminal as shown and described.

LOUIS A. KOCH, JR.
